FELTING METHOD AND MACHINE

Joseph A. Gould, Philadelphia, Pa.

Application August 5, 1942, Serial No. 453,612

8 Claims.

(Cl. 28—4)

This invention relates to a method and machine for making felt out of hair, jute or similar materials, the felt being loosely woven for the production, for example, of pads for use under rugs, though it will be understood that the product of the method and machine may vary substantially and be usable for other purposes.

In the production of such felt heretofore, a loose mass of hair or similar material has been compressed to a substantial extent and caused to pass beneath vertically moving needles provided with barbs, which in their movements catch the fibers pushing them downwardly through the mass and thus providing a sufficient interlocking to provide a product having substantial tensile strength. In such prior machines, however, it has been necessary to provide a backing of woven nature such as burlap, cheesecloth, or the like to support the felt, the tensile strength of which has been insufficient to enable it to withstand handling when in sheets of any substantial size. The securing of the felt to this backing was accomplished in the same operation which produced the felting by reason of the penetration of fiber loops into and through the woven material under the action of the needle barbs.

One object of the present invention is the provision of a method and machine of the general type indicated, but which is capable of producing a fabric having very high tensile strength so that it is entirely unnecessary to provide backing material of any sort. The improved felting operation is secured by the provision of feeding means capable of compacting the loose material to a very substantial extent at the point of penetration by the needles, together with the proper motion of the needles to secure very effective interweaving of the fibers and positive feed of the material.

The above and other objects of the invention, particularly relating to details of construction, will become apparent from the following description, read in conjunction with the accompanying drawings, in which:

Figure 1 is a plan view partially broken away showing the improved form of machine;

Figure 2 is a side elevation of the same;

Figure 3 is a vertical transverse section through the machine in the vicinity of the needles;

Figure 4 is a vertical section taken on the broken plane the trace of which is indicated at 4—4 in Figure 3;

Figure 5 is a perspective sectional view showing in particular the parts of the machine adjacent the needles;

Figure 6 is an enlarged sectional diagram show-

ing in particular the nature of the needle movement;

Figure 7 is a diagram showing an alternative arrangement of the grids compressing the material;

Figure 8 is a diagram showing the formation of a compact fabric by successive passage of material through a plurality of machines; and

Figure 9 is a diagram showing the lamination of a plurality of fabrics.

The machine comprises a frame consisting of various interconnected parts and including four upright posts 2 on pairs of which there reciprocate upwardly and downwardly cross-heads 4, one of which is located on each side of the machine. Extending through suitable bearings in these cross-heads is a shaft 6, to which is secured at one side of the machine an arm 8 carrying a pin 10 which is movable within a cam opening 14 in a plate 16 carried by the frame of the machine. Connecting rods 18 on opposite sides of the machine have their upper ends embracing the ends of the shaft 6 and their lower ends connected to crank pins 20 adjustable in radial slots 22 formed in crank discs 23 which are mounted on a driving shaft 24 rotated through motor and gear reduction connections to a sprocket 26.

To the portion of the shaft 6 between the cross-heads 4 there is welded or otherwise secured a plate 30 to which may be bolted the needle carrier 32 in openings in which are located needles 34, which are of conventional type, being of triangular or square cross-sections at their lower ends with downwardly opening barbs 36 formed in the edges between the flat surfaces. This arrangement of barbs causes them to engage and force downwardly fibers of the material to be felted, while presenting a smooth aspect to the fibers during upward motion so that the downwardly depressed loops are not pulled upwardly and remain in their depressed fiber-interlocking position.

The needles are arranged preferably in staggered relationship in groups of three or more arranged in the direction of movement of the material as indicated in Figure 5. The various individual groups of needles move between upper bars 38 and lower bars 40 forming upper and lower grids extending in the direction of motion of the material and serving to compress it during the felting operation. The lower bars 40 are secured to the frame of the machine, while the upper bars are provided in a unitary structure mounted for vertical adjustment by means of adjusting bolt 44 and nut arrangements indicated at 44. Thus the

spacing between the grids may be adjusted for any suitable thickness or compactness of the material. The upper grid unit carries a deflecting plate 42 extending across the machine and serving to lead the loose fibrous material into position between the grids under the action of the feeding means. For the purpose of feeding the material to the needles, there is provided a bed in the form of slats 46 extending in the direction of motion, these slats being provided with upwardly and forwardly directed pins 48, and being preferably aligned with the bars 40 of the lower grid. Between the slats 56 are arranged to reciprocate movable bars 50 which, at their forward ends may extend between the bars 40, their extreme forward movements, however, being such that they will not engage the needles. These movable bars 50 carry pins or barbs 52 similar to 48 and are arranged to be reciprocated back and forth in the direction of feed by connection to a common bracket 54 pivoted to the end 56 of the strap of an eccentric on the shaft 24.

For the purpose of removing the felted material from the region of the needles, a similar arrangement of fixed slats 58 and movable slats 60, provided with forwardly directed pins or barbs, is located beyond the region of the needles, the movable slats being reciprocated back and forth by means of connection to a common transverse bracket 62 pivoted to the end 64 of a second strap engaging another eccentric on the shaft 24.

In the operation of the machine, the various parts operate in proper timed relationship, secured by proper adjustment of the crank pins 20 and the eccentrics about the shaft 24. The loose fibrous material such as hair or jute is fed by hand as uniformly as possible upon the slats 46 and 50 or, in preference to this, may be fed thereto by unwinding a roll of conventional loose hair or jute batting such as is normally provided for feeding a felting machine. This loose and bulky material is engaged by the moving pins 48 and during their forward movement will be drawn freely over the fixed pins 52. When the slats 46 reverse their motion, the fixed pins 52 prevent the material from being drawn back therewith, and the pins 48 may slide freely relative to the material. Thus, as the moving slats reciprocate, the material is caused to move intermittently forward to a position beneath the deflecting and compressing plate 42. By reason of the feeding action and the presence of this plate, compacting of the material takes place and it is forced to pass between the grids 38 and 40 in position to be penetrated by the needles.

The needles not only have a vertical movement, but have an oscillating movement about the axis of the shaft 6 as well. As the shaft 6 moves upwardly, the pin 10 will engage the sloping upper portion of the boundary of the opening 14 with the result that the shaft will be oscillated in a clockwise direction as viewed in Figure 4, bringing the needles to their rearmost position. As they then move downwardly, their lower ends will follow the path indicated at A in Figure 6 until the pin engages the lower sloping edge of the opening 14, whereupon they will be oscillated forwardly during their downward movement along the path indicated at B. Thereafter, they move vertically upwardly along path C, and finally, when clear of the material, are oscillated backwardly along the path D, all of this occurring, as will be obvious, due to the shape of the

opening 14. The amount of oscillation imparted to the needles during the path B is such as to cause the needles to aid in feeding the material forwardly to an extent corresponding to that resulting from the action of the feeding slats. It may be noted, however, that this does not mean that the forward motion of the slats corresponds to the forward component of motion along the path B, since through the region between the grids 38 and 40, the material is compacted and its linear progress is substantially slower than that which would correspond to the motion of the moving grids.

As the product leaves the needles, it is picked up by the pins of the movable slats 60, the strokes of which are substantially less than the strokes of the moving slats 50 to secure a proper rate of feed. It is not to be understood, however, that the feed of material between the grids 38 and 40 is necessarily solely that determined by the oscillating movements of the needles. In fact, feed may take place during the time when the needles are out of the material due to the pushing action of the slats 50 and the pulling action of the slats 60. Various adjustments of timing in this respect are possible by suitable adjustment of the driving parts about the shaft 24.

The oscillating action of the needles is not solely for the purpose of feeding the material, but contributes very much toward the securing of a very strong material which does not require backing to give it a very high tensile strength. It will be evident that as the needle penetrates the material, during the period of initial penetration its oscillating movement will tend to move forwardly the uppermost portion of the material relative to the lowermost portion. The result is that in the finished material the loops and strands of fiber which are pushed downwardly by the needle barbs do not extend vertically through the material, but in diagonal directions, serving not only to increase greatly the tensile strength of the material, but also to hold it compacted by reason of the fact that a direct vertical pull or stress exerted by an attempted expansion of the fibers, cannot cause the interlacing or interlocking loops or strands to pull directly out of the material. As a result, in a single pass through the machine, a quite compact and strong felt is obtained.

In the present machine, as has been described, the grids 38 and 40 preferably extend in the direction of motion. This results, in a single pass of the material, in the formation of a ribbed material which is generally suitable for use. However, the grids may be arranged diagonally to the direction of motion, as diagrammed at 38' in Fig. 7, the direction of motion being indicated by the arrow, so as to produce, in effect, an ironing out of the material so that as it emerges from the machine its surfaces are flat. In such case, the diagonal angle of the grids and spaces between them must, of course, be so chosen as to permit of the desired needle oscillations in the direction of movement.

Reference has been made to a single pass of the material through the machine. In general, this is quite sufficient to secure a compact, strong felt. If greater compactness is desired, together with greater strength, the material may be repassed through the machine or several sheets each passed once through the machine may be passed together, one on top of the other through the machine, or the passage of one or several sheets may take place in a direction different from that

of the original passage. All of these procedures give rise to a more compact and stronger final material. For this same purpose, a series of machines may be arranged so as to act upon the material successively, in which case it may be desirable to have the grid spacing decrease through the series to secure greater compactness as indicated at G and G' in Fig. 8. Various other arrangements of such machines may, of course, be used, for example, two machines may deliver their sheets in overlapping relationship for passage through a third machine as indicated at H in Fig. 9. More than two plies may thus be passed through machines, the plies being interconnected by the fibers pushed downwardly from one ply into the other.

What I claim and desire to protect by Letters Patent is:

1. Apparatus for felting of fibrous material comprising a plurality of reciprocating barbed needles, means for holding compressed the fibrous material within a region of its penetration by the needles, and means for feeding loose fibrous material to said region comprising a series of alternately arranged stationary and reciprocating members provided with feeding barbs pointing in the direction of feed.

2. Apparatus for felting of fibrous material comprising a plurality of reciprocating barbed needles, means for holding compressed the fibrous material within a region of its penetration by the needles, means providing a converging space in advance of said region to compress said material, and means for feeding loose fibrous material to said region comprising a series of alternately arranged stationary and reciprocating members provided with feeding barbs pointing in the direction of feed.

3. Apparatus for felting of fibrous material comprising a plurality of reciprocating barbed needles, means for holding compressed the fibrous material within a region of its penetration by the needles, means for feeding loose fibrous material to said region comprising a series of alternately arranged stationary and reciprocating members provided with feeding barbs pointing in the direction of feed, and means for withdrawing from said region the material after penetration by the needles, said last means withdrawing the material at a linear rate less than the rate of feed of the loose material to the region.

4. Apparatus for felting of fibrous material comprising a plurality of reciprocating barbed needles, means for holding compressed the fibrous material within a region of its penetration by the needles, means for feeding loose fibrous material to said region comprising a series of alternately arranged stationary and reciprocating members provided with feeding barbs pointing in the direction of feed, and means for withdrawing from said region the material after penetration by the needles, said last means withdrawing the material at a linear rate less than the rate of feed of the loose material to the region, the last named means comprising a series of alternately arranged stationary and reciprocating members provided with feeding barbs pointing in the direction of feed.

5. The method of felting fibrous material comprising feeding the material to a region of compression wherein it is subjected to frictional retardation of its advance by members which are without movement in the direction of feed of the material and which engage the faces thereof, and in said region penetrating the material by means of barbed needles providing hooks opening towards their free ends and having components of motion in the direction of the material feed while the free ends of the needles are passing into the material to force fibrous loops thereto, thereby to effect differential feed of portions of the material between the opposite surfaces thereof.

6. The method of felting fibrous material comprising feeding the material to a region of compression wherein it is subjected to frictional retardation of its advance by members which are without movement in the direction of feed of the material and which engage the faces thereof, and in said region penetrating the material by means of barbed needles providing hooks opening towards their free ends and having components of motion in the direction of the material feed while the free ends of the needles are passing into the material to force fibrous loops thereto, thereby to effect differential feed of portions of the material between the opposite surfaces thereof.

7. Apparatus for the felting of fibrous material comprising a plurality of reciprocating barbed needles providing hooks opening towards their free ends, means for holding compressed, and retarding movement of, the fibrous material within a region of its penetration by the needles, means for feeding loose fibrous material to said region, the compressing means being without movement in the direction of such feed, and means for imparting to the needles components of motion in the direction of the material feed while the free ends of the needles are passing into the material and forcing fibrous loops thereto, thereby to effect differential feed of portions of the material between the opposite surfaces thereof.

8. Apparatus for the felting of fibrous material comprising a plurality of reciprocating barbed needles providing hooks opening towards their free ends, means for holding compressed, and retarding movement of, the fibrous material within a region of its penetration by the needles, means for feeding loose fibrous material to said region, the compressing means being without movement in the direction of such feed, and means for imparting to the needles components of motion in the direction of the material feed while the free ends of the needles are passing into the material and forcing fibrous loops thereto and for withdrawing the needles from the material without any substantial component of motion in the direction of feed, thereby to effect differential feed of portions of the material between the opposite surfaces thereof.

JOSEPH A. GOULD.
